UNITED STATES PATENT OFFICE.

ALBERT STEFFIN, OF NEW BEDFORD, MASSACHUSETTS.

DESIGN FOR A SALT-BOX OR CONDIMENTS-HOLDER.

SPECIFICATION forming part of Design No. 19,120, dated May 28, 1889.

Application filed November 10, 1887. Serial No. 254,859. Term of patent 7 years.

To all whom it may concern:

Be it known that I, ALBERT STEFFIN, a citizen of the United States, residing at New Bedford, in the county of Bristol and State of Massachusetts, have invented a certain new and useful Design for Salt-Boxes or Condiment Holders and Distributors, of which the following is a specification, reference being had to the accompanying drawings.

10 My invention consists in a new and original design for salt-boxes or condiment holders and distributors, which represents the form of an egg with a flattened base, containing the following features.

15 The accompanying drawings illustrate my design, in which—

Figure 1 shows the box with the cap in place, while Fig. 2 shows the same with the cap raised.

The body A B is oval in form, having a truncated base, a perforated cap or top, B, and 20 the line of demarkation b, the body being decorated with artistic decorations C, giving the article a unique and tasteful appearance.

I claim as my invention—

A design for salt-boxes or condiment-holders, consisting of a body of oval shape having a truncated base, the perforated top and line of demarkation b, and provided with an ornamented surface, as shown.

In testimony whereof I affix my signature in 30 presence of two witnesses.

ALBERT STEFFIN.
